(57) **CLAIM**

The ornamental design for a gauge display mount, as shown and described.

DESCRIPTION

FIG. 1 is a top left front perspective view of a gauge display mount showing our new design.

FIG. 2 is a bottom right front perspective view of the gauge display mount of FIG. 1;

FIG. 3 is a top plan view of the gauge display mount of FIG. 1;

FIG. 4 is a rear elevational view of the gauge display mount of FIG. 1;

FIG. 5 is a left side elevational view of the gauge display mount of FIG. 1; and,

FIG. 6 is a right side elevational view of the gauge display mount of FIG. 1.

The broken line showing of gauge display mount extension and support base is for illustrative purposes only and forms no part of the claimed design.
